RADIO SIGNALING SYSTEM

Edwin H. Armstrong, New York, N. Y.

Application August 6, 1927, Serial No. 211,046
Renewed November 9, 1933

14 Claims. (Cl. 250—8)

This invention relates to radio signaling and has for its principal ultimate object to provide a method of and apparatus for the reduction of atmospheric disturbances in radio signaling.

Another object is to provide a radio signaling system which, for a given amount of energy transmitted and a given distance of transmission, causes a much greater response in the receiver than in the case of systems now in use; and/or for a given amount of energy transmitted and a given desired magnitude of response in the receiver, greatly increases the distance of transmission over that obtained with systems now in use.

Further objects and advantages will appear as the invention is hereinafter disclosed and claimed.

The difficulty of the problem of static interference (undesired atmospheric disturbances) is due to the fact that these disturbances act, in effect, as a band of frequencies, and that some component has substantially the same frequency characteristic as the signal which it is endeavored to receive, and that this component passing through the selective devices creates interfering responses in the indicator.

The present method is based on the discovery that the distribution of energy with respect to frequency of the natural waves is such that at any instant the energy in the component at a given frequency is substantially equal to the energy at a closely adjacent frequency, and that in a "crash" or "burst" of static both these frequencies will be present simultaneously.

In accordance with the now preferred method of the present invention, a special form of signaling wave is employed at the transmitter and a novel method of electrical selection at the receiver. The special form of transmitted wave has a characteristic not found in the waves of natural origin.

The apparatus hereinafter disclosed employing the new method of electrical selection has the characteristic of acting cumulatively with respect to the signaling waves but differentially with respect to the waves of natural origin, so that the first are augmented but the latter substantially balanced out.

In accordance with the form of the present invention hereinafter disclosed, signaling is accomplished by transmitting alternately two frequencies, both of which are used, one frequency as the marking wave and another close to it as the spacing wave. The difference between these two frequencies is determined by considerations

which will be explained hereinafter, being made sufficiently small so that both frequencies are received with equal facility.

Reception is accomplished by an arrangement of apparatus which is capable of separating practically instantaneously the two desired frequencies and which is so arranged that an opposite effect is produced on the indicator by one frequency when present alone as compared to the effect produced by the other frequency when present alone. When both frequencies are present, as in static disturbances, the effects on the indicator substantially cancel or neutralize each other. In general the result is obtained by integrating the received frequencies and causing the resultant effects to act cumulatively or differentially on the indicator as the case may be.

Referring to the drawings which illustrate and explain what I now consider preferred apparatus for carrying the invention into practice:

Fig. 1 diagrammatically illustrates the transmitting apparatus.

Fig. 2 diagrammatically illustrates the receiving apparatus.

Fig. 3 illustrates the characteristic curve of the selector C, shown in Fig. 2, when straight line rectification is accomplished.

Fig. 4 illustrates the combined characteristic curve of the filter equalizer B and the selector C, shown in Fig. 2, for signal strength sufficient to give straight line rectification.

Figs. 5 to 12, inclusive, are copies of tape records made as hereinafter explained.

Referring now to Fig. 1 which illustrates the transmitter, a regenerative oscillator 1, 2, 3, is provided with small condenser 4 in its frequency-controlling circuit arranged to be cut in by a key 5. The value of the condenser 4 is arranged in the case of a long wave transmitter, to change the frequency by an amount lying between, say, 25 to 100 cycles. In the case of a short wave transmitter it may be advantageous to use a frequency change which is greater than in the case of long wave transmission although the increase required is much less than that which would be proportionate to the increase in the generated frequency. A power amplifier system 6, 7, 8, is shown connected to the antenna system 9, 10, and to the output side of the oscillator system.

The construction and operation of the transmitting system will be appreciated by those skilled in the art, in view of the foregoing description. The regenerative oscillator system 1, 2, 3 (including the three-electrode vacuum tube 1) gener-

ates oscillations of one predetermined frequency when the key 5 is open and oscillations of a different predetermined frequency when the key 5 is closed. The oscillations so generated are amplified by the power amplifier system 6, 7, 8 (including the three-electrode vacuum tube 7), and fed into the antenna system 9, 10.

Referring now to Fig. 2, A represents a standard form of heterodyne receiver with the usual tuned circuit 12, 13 coupled at 11—12 to the receiving antenna or collector and having the usual tuned amplifier 14 between the circuit 12—13 and the rectifier 16. An audio frequency amplifier 18 of considerable power is coupled to the output of 15 the rectifier at 17. Locally generated oscillations under suitable control are supplied at 15 to the input of the rectifier 16 (a three-electrode vacuum tube) to be combined with the incoming or received frequencies by the well known heterodyne method.

B represents a form of filtering device, one section of which is adapted to pass one of the signaling frequencies and the other section of which is adapted to pass the other signaling frequency, 25 and which is so arranged and controlled as to equalize the amplitude of the disturbance created by static on these two frequencies. The function of this equalizer and its manner of operation will be set forth hereinafter.

30 The equalizer system B is connected or coupled at 19 at its input side to the output side of the audio amplifier 18, and at its output side to the input side of the selector system C. The system B is shown as comprising two tubes 25, 26, which 35 are three-electrode vacuum tubes. The grid circuits of these tubes 25 and 26 are connected to the secondary of the transformer 19; suitable resistances for adjusting the damping are shown in the circuits. The grid circuits of the tubes 25 40 and 26 are tuned by the tuning elements 21, 23, and 22, 24 respectively. The output or plate circuits of the tubes 25, 26 are respectively connected to corresponding ones of the primary windings of the transformers 27, 28. One terminal 45 of one secondary winding is shown connected to one terminal of the other secondary winding. Each of these secondaries is shown shunted by a corresponding one of two resistances 29, 30, each provided with an adjustable tap, each tap being 50 connected to the input of the selector system C.

The system B is so designed and adjusted as to accomplish the following functions, among others: to pass with equal facility each of the two transmitted frequencies and to cut off those 55 on either side (i. e. above the higher frequency and below the lower frequency) and also substantially to equalize with respect to each other the amplitudes of the static disturbances occurring above and below a certain frequency (F_3 , hereinafter referred to) which lies midway between the two transmitted frequencies. To effect these functions, the output transformers 27, 28 are so connected that, were the circuits 21, 23, and 22, 24, tuned to the same frequency, and the 65 relative amplitudes properly adjusted by means of the potentiometers 29, 30, the outputs of these transformers 27 and 28 would neutralize each other. The circuits 21, 23, and 22, 24 are tuned respectively to the two signaling frequencies produced in the output circuit of the rectifier 16.

The selector system C has the important property or ability of distinguishing and distinguishing practically instantaneously between two frequencies which are close to each other. It 75 comprises an inductance 34 and two condensers 32,

33, connected as shown. Anticipating somewhat the more complete explanation of operation hereinafter set forth, for facilitating the disclosure: two different signaling frequencies are alternately impressed upon the input of the selector system 5 C. The combination of the inductance 34 and condenser 33 is so designed and/or adjusted as to give substantially zero potential across the upper terminal of the condenser 33 and the lower terminal of the inductance 34. In other words, 10 the design and/or adjustment of the inductance 34 and condenser 33 are such that the circuit between the outer ends of the condenser and inductance is non-reactive for one of the two signaling frequencies supplied to the selector system 15 C. The combination of the inductance 34 and both capacities 33 and 32 is so designed and/or adjusted that the circuit between the upper end of the condenser 32 and the lower end of the inductance 34, is non-reactive for the other 20 of the two signaling frequencies supplied to the selector system C. An amplifier 40 which is preferably a three-electrode vacuum tube amplifier, has its grid or input circuit connected (through a transformer 38) across the combination: inductance 34—condenser 33. A similar amplifier 41 has its grid or input circuit connected (through a transformer 39) across the combination: inductance 34—condenser 33—condenser 32. It will be noted that the primaries of the input 30 transformers of the amplifiers 40, 41 have a common connection to the lower end of the inductance 34 through a resistance 37. A resistance 35 is connected at one terminal to the lower end of the inductance 34 and at its other end to one of the 35 leads from the output of the equalizer B and also to the grid of a three electrode vacuum tube amplifier 36; the filament of the latter being connected to the terminal of the resistance 35 that connects to the coil 34. The plate circuit of the 40 tube 36 includes the resistance 37 and is connected to the common lead of the transformer 38, 39, as shown. The function of the tube 36 and connections is that of a resistance compensator, i. e. to cause the system to act as though 45 the inductance 34, and condensers 33, 32, had no resistance.

Each of the amplifiers 40, 41, has its output circuit connected or coupled through a corresponding one of two transformers 42, 43, to the 50 input side of a corresponding one of two rectifiers 46, 47. These are preferably two-electrode vacuum tubes or so-called Fleming valves. Each of the rectifiers includes a comparatively large resistance 44, 45 connected as shown, for the 55 purpose of producing substantially straight-line rectification of the currents being dealt with. Such straight line rectification is disclosed and explained in my co-pending application, Serial No. 538,856, filed February 24, 1922, now Patent 60 No. 1,716,573, patented June 11, 1929. The output of the rectifiers 46, 47, connected as shown, goes to a filter system D hereinafter described.

Again anticipating the description of operation set forth hereinafter, the operation of the selector system C may conveniently now be explained in part.

The characteristic curve of the response of the selector system C as measured by the combined output of the rectifiers 46, 47 for varying frequency supplied to the input side, is shown in Fig. 3. The approach of this curve to the ideal condition results from the provision of the resistance compensator 35—36—37 previously described. The resistance 35 is a comparatively 70 75

small resistance, preferably less than the resistance to be compensated for, and the resistance 37 is a large resistance. By proper adjustment of these resistances with respect to each other, the resistance drop across the reactance combinations 34-33 and 34-33-32 is minimized and the ideal curve is approached.

As shown in the characteristic curve (Fig. 3), as the frequency of the input current to the selector system C is increased, the rectified current does not vary materially until a certain frequency F_1 is reached. Further increase in frequency causes decrease in the rectified current until it reaches zero at a certain frequency F_3 . Still further increase of input frequency causes the output current to flow in the opposite direction and to increase with frequency until a certain frequency F_2 is reached, beyond which the current again does not vary materially for further increase of frequency.

I wish to emphasize an important property of the selector system C; i. e., that it distinguishes practically instantaneously between frequencies supplied to it as compared to the time required for the usual circuit, tuned to resonance for a predetermined frequency, to distinguish between that frequency and other frequencies.

The combined characteristic curve of the equalizer B and the selector system C is shown in Fig. 4 where it will be noted that the frequencies above F_2 and below F_1 are substantially cut off. It will be noted further, as set forth in connection with Fig. 3, that frequencies between F_1 and F_3 (impressed upon the input to equalizer B and supplied from it to the input of the selector system C) produce a rectified current which flows in one direction in the output of the selector system C, and that frequencies which lie between F_3 and F_2 produce a rectified current that flows in the opposite direction. The importance of this characteristic or property will be more fully appreciated upon review of the complete description of the operation.

The filter system D (see Fig. 2), which receives the output of the selector system C, is shown as comprising an inductance 48, resistances 49, 51, and condensers 50, 52, connected as shown. The design and connections are such that this filter system D will pass continuous current or currents of comparatively low frequency but substantially cut off currents of comparatively high frequencies. As will hereinafter more clearly appear, the adjustment of this filter depends upon the speed of signaling and the relative strength of the atmospheric disturbances to the signal strength. The inductance or choke coil 48 serves also to prevent the passage to the amplifier 53 of alternating currents which would paralyze or tend to paralyze it in the absence of such preventive means.

The output of the filter system D is shown connected to a D. C. amplifier 53 of usual construction, whose output connects through a potentiometer-controlled source 57, of direct current (connected as shown), through a switch to a siphon recorder 54 (of the type now commonly employed in practice in the art to which the present invention relates) or to the usual head phones 55 having a chopper 56 in its circuit.

The system is preferably designed, constructed, and adjusted, to operate substantially as follows. Assume that the transmitter (Fig. 1) is so adjusted as to send at a frequency of 20,000 cycles per second when the key 5 is down, and at a frequency of 20,050 cycles when the key 5 is up,

and that the key 5 is employed to transmit signals by the usual code of properly spaced dots and dashes and combinations thereof. To receive the signals so transmitted the receiving system (Fig. 2) may be adjusted as follows. The input circuits 11, 12, 13, etc., of the system A are tuned to pass the transmitted frequencies of 20,000 and 20,050 cycles and the local source of oscillations supplied at 15 so adjusted to produce, in the output of the system A, a beat frequency of 1550 cycles when the frequency of 20,050 cycles is being received, and a beat frequency of 1500 cycles when the frequency of 20,000 cycles is being received. These two beat frequencies which occur alternately are supplied to the equalizer system B. The circuit 21, 23 of the system B is tuned to one of these beat frequencies and the circuit 22, 24 is tuned to the other beat frequency. The circuits of the selector system C are so adjusted that the frequency F_1 (see Figs. 3 and 4) is 1500 cycles per second and the frequency F_2 is 1550 cycles per second. When the key 5 (Fig. 1) is down (i. e., on front stroke to make a dot or dash depending on the comparative length of time it is held down), a frequency of 20,000 cycles is transmitted. By beating down in the receiver, this frequency of 20,000 cycles is converted into the frequency of 1500 cycles (F_1) which produces, in the output of the selector system C, a rectified current having the value (see Figs. 3 and 4) corresponding to F_1 . This rectified current flows through the filter system D, is then amplified by the D. C. amplifier 53 and gives a deflection on the siphon recorder 54 (assuming of course that the latter is connected by the switch to the output of the amplifier 53) corresponding to the amplitude and polarity of the amplified rectified current. The siphon recorder 54 is a polarized instrument and its stylus is deflected from its neutral position in one direction or the other depending upon the polarity of the rectified current. It will be understood that the deflection of the stylus by the current described will persist for a length of time the transmitting key 5 (Fig. 1) is held down.

When the transmitting key 5 (Fig. 1) is released; i. e., open, (i. e., on spacing or back stroke), the operation is similar to that set forth above, in connection with the key 5 closed, except as now noted. In this case the beat current of 1550 cycles (F_2) is produced in the receiver. This produces a rectified current corresponding in amplitude and direction to that indicated for F_2 in Figs. 3 and 4. It will be noted that this rectified current is of substantially the same amplitude as that produced by reception of the frequency of 20,000 cycles transmitted when the key 5 is depressed, but it is of opposite polarity. This rectified current (key 5 up or open) causes the stylus of the siphon recorder 54 to return to 60 and pass through its neutral position and to be deflected in the direction opposite to that in which it is deflected when the key 5 is closed or depressed.

It is important to note that the deflection of the recording stylus obtained by virtue of the system herein disclosed is double that obtained from the standard systems now in use. This doubling of deflection corresponds to what would be obtained by quadrupling the energy transmitted by 70 a standard system, other conditions being the same in the two cases. Therefore, wholly aside from the reduction of static or atmospheric interference, I have provided a radio signaling system of much greater economic efficiency than the 75

radio telegraph systems now in commercial use. In addition, as stated, I have provided a novel system of radio communication in which the disturbing effect of static or atmospherics is greatly reduced. This aspect of the operation of the system will now be dealt with by considering what happens in the receiving system when a band of frequencies, such as is contained in a group of atmospheric discharges, is received.

Over a comparatively short interval of time there will be substantially the same amount of energy impressed by the static or atmospherics upon the input of the selector system C between the frequencies F_1 and F_3 as between the frequencies F_3 and F_2 . Over short intervals of time, due in part to inequalities of heterodyning because of the particular phase of the heterodyning current with respect to the phase of the incoming disturbances, more energy may be in the lower or higher of the two frequency bands. The equalizer B reduces this inequality so that there are delivered to the selector system C two bands of frequencies of practically the same energy. These two bands are separated in the selector system C into high and low frequency groups, which are supplied respectively to the rectifiers 46, 47, converted thereby into rectified form, and the two rectified outputs differentially combined to oppose and substantially neutralize each other.

While over a period of time the balance is practically perfect, over short intervals of time it happens that the lower of the two frequency bands produces a greater amount of energy and a larger value of rectified current than the higher frequency band, and vice versa. This results in the presence in the output of the selector system of a residual disturbance which is an alternating current of irregular frequency which more or less rapidly reverses. Since the current produced in the receiving system, and present in the output of the selector system C, by the energy transmitted at the transmitting station during the intervals of a dot, a dash, or a space, is substantially a continuous current (or at very high speeds of sending, a lower frequency current than the residual disturbances), the filter system may be and preferably is provided and adjusted so as to block the passage of the residual disturbances to the signal-indicating device 54 or 55.

To the best of my present ability and knowledge I have set forth the theories and explanations upon which I now believe the operation of my features of invention depends, and whereby they may be practiced by those skilled in the art having the foregoing disclosures before them. These theories and explanations appear to be borne out by extended tests and demonstrations that I have made. However, it may later appear in the light of further development that the theories and/or explanations advanced are not wholly accurate, and I shall therefore in addition disclose in considerable detail a physical embodiment of the invention and results I have obtained with it.

The transmitting apparatus was adjusted to generate and emit oscillations at a frequency of 20,060 cycles per second with the key 5 (Fig. 1) raised or open and at a frequency of 20,000 cycles per second with the key 5 down or closed. No further comment need be made with respect to the adjustment of the transmitter.

The receiving system embodied as its col-

lector of energy on outdoor antenna and the static impressed upon it was natural as distinguished from artificially created static. The signals were impressed upon the receiving antenna from the oscillation-generator whose oscillations, as stated, were transmitted at a frequency of 20,060 cycles per second with the key 5 up and at a frequency of 20,000 cycles per second when the key 5 was down. I shall now proceed to give such information and constants of the receiving apparatus employed by me (see Fig. 2) as will enable those skilled in the art to reproduce it and the results obtained with it.

The apparatus A was standard apparatus and needs no further comment. The transformer 19 was a step-down transformer having a ratio of transformation of 10 to 1; the resistance 20 was variable from a few ohms to 100 ohms and adjusted according to the speed of signaling; the inductance 21 was 0.34 henry; the inductance 22 was 0.31 henry; the condenser 23 had a capacity of 0.05 microfarad; the condenser 24 had a capacity of 0.05 microfarad; the transformers 27, 28 were step-down transformers each having a ratio of transformation of 4 to 1; the resistances 29, 30 each had a maximum resistance of 400 ohms; the condenser 32 had a capacity of 0.5 microfarad; the condenser 33 had a capacity of 0.05 microfarad; the inductance 34 was 0.34 henry; the resistance 35 was variable between a few ohms and 100 ohms; the resistance 37 was 4000 ohms; 38, 39 were ordinary audio frequency intertube transformers; 40, 41 were standard three-electrode vacuum tube amplifiers; 42 and 43 were ordinary output transformers each having a ratio of one to one; 44 and 45 each had a resistance of 6000 ohms; 48 was a choke coil of about 25 henrys; 49 and 51 were each variable between 25,000 ohms and 50,000 ohms in steps; 50 and 52 were each variable between zero and 0.1 microfarad in steps; and 53, 54, etc. were standard apparatus previously described needing no further comment. The circuits 12, 13, 14 were tuned to admit either of the transmitted frequencies, i. e. 20,000 and 20,060 cycles per second; the local generator of oscillations was adjusted to supply, at 15, oscillations at a frequency of 21,280 cycles per second, producing with the received frequency of 20,060 a beat frequency of 1220 cycles per second and producing with the received frequency of 20,000 a beat frequency of 1280 cycles per second. The circuit 21-23 was tuned to one of the signal beat frequencies—1220 cycles per second, and the circuit 22-24 was tuned to the other signal beat frequency—1280 cycles per second, the F_3 frequency being about 1250 cycles per second.

In Figs. 5, 6 and 7, I have shown copies of some tape records made with my apparatus above described when no static or interfering energy was impressed upon the antenna of the receiver. The tape record reproduced as Fig. 5 was made by first establishing the base line in the middle of the tape with the transmitter dead (i. e., with the plate circuit of the oscillator tube of the transmitter open), then closing the key 5 and keeping it closed while interrupting the plate current (in the usual manner by a key not shown) of the oscillator tube of the transmitter to cause the dot and dash signals to be transmitted. The tape record reproduced as Fig. 6 was similarly obtained but with the key 5 open so that the condenser 4 was not in circuit. It will be noted that in one case the stylus was deflected in one direction from the base line (middle) on the marking 75

strokes and returned to the base line (middle) on the spacing strokes, while in the other case the stylus was deflected in the opposite direction from the base line (middle) on the marking strokes, returning to the base line (middle) on the spacing strokes. The tape record reproduced as Fig. 7 was made by first establishing the middle line with the transmitter dead, as in the case of Figs. 5 and 6. The plate circuit of the oscillator tube 10 of the transmitter was then permanently closed, and the key 5 employed to cause the dot and dash signals to be transmitted.

Comparison of the actual record shown in Fig. 7 with those shown in Figs. 5 and 6 confirms the statements that I have previously made, i. e. that the deflection of the recording stylus (Fig. 7) obtainable by virtue of my invention is double that obtainable from standard methods of signaling, and that, therefore, wholly aside from the reduction of static or atmospheric interference, I have provided a radio signaling system of greatly improved economic efficiency.

In Figs. 8, 9 and 10 are reproduced actual tape records showing the effect of natural static impressed upon, i. e. received by, the receiving antenna, no signal being received. The base lines of these records are at the middle of the tape in each instance. The curve reproduced in Fig. 8 was made by removing one of the tubes 46, 47 from the system, i. e. working only one side of the balance, and the curve reproduced in Fig. 9 was made by replacing the tube previously removed and removing the other of the tubes 46, 47, i. e. working only the other side of the balance. The record reproduced in Fig. 10 was made with both sides of the balance in operation.

It will be seen that whereas the signal frequencies act cumulatively in producing indications (Fig. 7), the energy of static frequencies 40 above the mid-frequency F_3 acts differentially with respect to the energy of the static frequencies below the mid-frequency F_3 (Fig. 10). It will be noted also that in Fig. 8, as in the case of standard systems, the static-produced impulses 45 are above the base line and produce a varying unidirectional current which cannot be successfully filtered out if present alone. However, in my system there is simultaneously produced (Fig. 9), by the static, varying unidirectional current 50 of opposite polarity, which when differentially combined with the first mentioned unidirectional current leaves only a residual (Fig. 10) having no substantial direct current component but which is a current which fairly rapidly reverses in polarity and may be successfully filtered out.

The tape record reproduced in Fig. 11 was made with standard receiving apparatus, while that reproduced in Fig. 12 was made with my apparatus embodying my invention.

In both cases; the same code signals were transmitted and received and at the same speed. The two records were made closely in succession in point of time with the same outdoor receiving antenna subjected to substantially the same natural static in both cases. The effect of the static upon the indications with the standard receiver are clearly apparent in Fig. 11. In the case of my apparatus embodying my invention the static disturbances, which in the case of the standard 60 method of reception were sufficient to prevent operation, were practically eliminated and do not appear in the record of the indications (Fig. 12). It will be apparent that the signals recorded on the tape reproduced in Fig. 12 could have been 70 transmitted and recorded at very much greater

speed before reaching a condition in which their readability would be impaired.

It will now be apparent that, in addition to increasing the economic efficiency of radio signaling by virtue of the double deflection obtainable 5 and spoken of hereinbefore, my invention effects great improvement in the economic efficiency by virtue of the reduction of the disturbing effects of static or atmospherics. For the same degree of readability the speed of transmission and reception may be greatly increased as compared to that obtainable with the standard 10 methods of signaling. Furthermore, it renders possible facsimile transmission under static conditions and at such speeds impossible with the 15 standard systems now in use.

In view of the foregoing disclosure, it will be understood of course, that the frequencies supplied to the more important parts of my system, for example, to the input of the equalizer B, need 20 not be audible frequencies but may be radio or intermediate frequencies. In other words, the frequencies F_1 , F_2 and F_3 (Figs. 3 and 4) may have other numerical values than those hereinbefore specifically mentioned or referred to, by 25 suitably selecting the constants in accordance with the principles disclosed.

It will be further understood that certain features of my invention above disclosed may, within the scope of appended claims, be modified 30 and/or omitted depending upon the extent to which the improved results are desired, and that certain instrumentalities and/or groups of instrumentalities may be employed in radio signaling systems in which other results are attained. Thus it will be apparent that some of the features of invention herein disclosed are claimed in my Patent No. 1,941,447, granted December 26, 1934.

What I claim is:—

1. The method of reducing the effects in radio signaling of atmospheric disturbances consisting of simultaneously occurring frequencies, which method comprises alternately changing the signaling frequency at the transmitting station, 45 impressing the signal oscillations of different frequencies successively upon the receiving system, causing the successively applied different signal frequencies to act cumulatively in producing indications, causing the received atmospheric 50 frequencies to act differentially with respect to each other to reduce their interference with the production of the signal-representing indications, and adjusting the differential action under varying conditions to cause the effect produced by 55 a portion of the received disturbances to be substantially equal to the opposite effect produced by the remainder of the received disturbances.

2. In radio reception, the method of rejecting 60 undesired simultaneously received different frequencies and selecting alternately received different signal frequencies, which method comprises causing the alternately received different signal frequencies to act cumulatively, causing the undesired frequencies to act differentially 65 with respect to each other, and adjusting the differential action under varying conditions to cause the effect produced by a portion of the undesired frequencies to be substantially equal to the opposite effect produced by the remainder 70 of the undesired frequencies.

3. A method of increasing the extent of the signal-recording stroke of the signal-recording stylus in the receiver of a radio telegraph system in response to transmitted radio telegraph 75

signals, which method comprises transmitting oscillations of one frequency during spacing intervals, transmitting oscillations of a different frequency during other signaling intervals, impressing said oscillations upon a receiving system, causing the oscillations of the first mentioned frequency to produce a deflection of a recording stylus in one direction from neutral position, and causing the oscillations of the second mentioned frequency to produce a deflection of the recording stylus in the opposite direction from neutral position.

4. The method of reducing the effect in radio signaling of atmospheric disturbances consisting of simultaneously occurring frequencies, which method comprises causing received frequencies above a predetermined frequency to produce a rectified current in one direction, causing received frequencies below said predetermined frequency to produce a rectified current in the opposite direction, differentially combining said rectified currents, and filtering out undesired residual currents.

5. The method of reducing the effects in radio reception of atmospheric disturbances consisting of simultaneously occurring frequencies, which method comprises substantially equalizing the energy produced by received static frequency components above a predetermined frequency with respect to that produced by received static frequency components below said predetermined frequency, causing the first mentioned energy to produce a rectified current in one direction and causing the second mentioned energy to produce a rectified current in the opposite direction, differentially combining said rectified currents, and filtering out undesired residual currents.

6. Apparatus for increasing the extent of the signal-recording stroke of the signal-recording stylus in the receiver of a radio telegraph system in response to transmitted radio telegraph signals, the said apparatus comprising in combination, transmitting means including a key, means for transmitting oscillations at a predetermined frequency upon closure of said key, and means for transmitting oscillations at a different predetermined frequency upon release of said key; and receiving means comprising a recording device and frequency responsive means for causing movement of the stylus of said recorder in one direction upon reception of oscillations at one of said predetermined frequencies and for causing movement of the stylus of said recorder in the opposite direction upon reception of oscillations at the other of said predetermined frequencies.

7. In a system of the class described, energy-equalizing means comprising in combination, a first tuned circuit, a second tuned circuit, means for supplying energy jointly to said circuits, a three-electrode vacuum tube having a grid circuit connected to said first mentioned circuit, a three-electrode vacuum tube having its grid circuit connected to said second mentioned circuit, a pair of transformers each of which has its primary winding connected to the plate circuit of a corresponding one of said vacuum tubes and one terminal of one secondary winding connected to one terminal of the other secondary winding, a resistance connected across one of said secondary windings, a resistance connected across the other of said secondary windings, and a circuit connected across said resistances.

8. The method of reducing the effects in radio signaling of atmospheric disturbances consisting

of simultaneously occurring frequencies, which method comprises alternately changing the signaling frequency at the transmitting station, impressing the signal oscillations of different frequencies successively upon the receiving system, causing the successively applied different signal frequencies to act cumulatively in producing indications, causing a portion of the received atmospheric disturbances to produce a current of one polarity, causing another portion of the received atmospheric disturbances to produce a current of opposite polarity, and combining said two currents of opposite polarity.

9. The method of reducing the effects in radio signaling of atmospheric disturbances consisting of simultaneously occurring frequencies, which method comprises alternately changing the signaling frequency at the transmitting station, impressing the signal oscillations of different frequencies successively upon the receiving system, causing the successively applied different signal frequencies to act cumulatively in producing indications, causing a portion of the received atmospheric disturbances to produce a current of one polarity, causing another portion of the received atmospheric disturbances to produce a current of opposite polarity and filtering the combined current produced by the two last mentioned currents.

10. A radio signaling system comprising in combination, an indication-controlling circuit, means for producing in said circuit a signal-controlling current which reverses in direction comparatively slowly, means for causing a portion of undesired received energy to produce a substantially unidirectional varying current in said circuit, means for causing another portion of the undesired received energy to produce in said circuit a substantially unidirectional varying current of opposite polarity to said second mentioned current, and means connected to said circuit for impeding the passage of the combined current produced by the undesired energy but permitting the passage of the signal-controlling current.

11. In a radio receiving system, in combination, a group of reactance elements which are non-reactive at a certain frequency, another group of reactance elements which are non-reactive at a different frequency, means controlled by received oscillations for causing currents to flow through said groups of reactance elements, a circuit connected across the first mentioned group of reactance elements, a rectifier controlled by said circuit, a circuit connected across the second mentioned group of reactance elements, a rectifier controlled by said last mentioned circuits, means for differentially combining the outputs of said rectifiers, indicating means controlled by said rectifiers, and means for substantially eliminating the effect of the resistance of each of said groups of reactance elements.

12. The method of reducing fading when transmitting code signals on short waves which includes keying the transmitter with a slightly different frequency back wave for the spacing periods, and radiating the marking and spacing energies alternately, and at the receiver, collecting the radiated energies, heterodyning the collected energies to energies of intermediate frequency, separating the marking and spacing intermediate frequency energies, separately rectifying the marking and spacing energies, reversing the phase of one of the rectified energies, combining the rectified energies, and translating the combined energies, whereby both and also

either of the marking and spacing energies alone will produce a readable signal.

13. An arrangement for reducing fading when transmitting code signals on short waves including a transmission system comprising a short wave transmitter, keying means arranged to slightly change the frequency of transmission in order to distinguish between marking and spacing periods, and means to radiate the marking and spacing energies alternately, and a receiving system comprising means to collect the radiated energies, means to separate the marking and spacing energies, means to separately rectify the marking and spacing energies, and a translating device responsive to one of the rectified energies in one sense, and to the other of the rectified energies in the opposite sense, so that both or either of the marking and spacing energies will produce a readable signal.

14. An arrangement for reducing fading when

transmitting code signals on short waves including a transmission system comprising a short wave transmitter, keying means for slightly changing the frequency of transmission to distinguish between marking and spacing periods, and means to radiate the marking and spacing energies alternately, and a receiving system comprising means to collect the radiated energies, means to heterodyne the collected energies to energies of intermediate frequency, means to separate the marking and spacing intermediate frequency energies, means to separately rectify the marking and spacing energies, means to reverse the phase of one of the rectified energies, means to combine the resulting energies, and means to translate the combined energy, so that both or either of the marking and spacing energies will produce a readable signal.
